CLAIM

The ornamental design for a combined carpet cleaning wand and head therefor, as shown and described.

DESCRIPTION

FIG. 1 is a front left perspective view of a combined carpet cleaning wand and head therefor showing my new design;

FIG. 2 is a left side elevation shown on a reduced scale;
FIG. 3 is a right side elevation thereof;

FIG. 4 is a front elevation thereof;

FIG. 5 is a rear elevation thereof;

FIG. 6 is a top plan view thereof;

FIG. 7 is a bottom plan view thereof; and,

FIG. 8 is a rear perspective view to the same scale as
